LIGHTING FIXTURE LOUVER

Robert G. Marchisio, Wenham, Mass., assignor to
Sylvania Electric Products Inc., Salem, Mass., a
corporation of Massachusetts

Application February 27, 1951, Serial No. 14,326

Term of patent 14 years

(Cl. D48—33)

To all whom it may concern:

Be it known that I, Robert G. Marchisio, a citizen of the United States, residing at Wenham, in the county of Essex and State of Massachusetts, have invented a new, original, and ornamental Design for a Lighting Fixture Louver, of which the following is a specification, reference being had to the accompanying drawing, forming part thereof,

Figure 1 is a plan view of a lighting fixture louver showing my new design.

Figure 2 is a side elevational view thereof.

Figure 3 is a perspective view thereof.

Figure 4 is a fragmentary cross-sectional view thereof drawn to a larger scale and taken on the line 4—4 of Figure 1.

The dotted lines shown in the drawing are for illustrative purposes only.

I claim:

The ornamental design for a lighting fixture louver, as shown and described.

ROBERT G. MARCHISIO.
